UNITED STATES PATENT OFFICE.

JULIUS FRED HECKMANN, OF LUPUS, MISSOURI.

GUN-MAGAZINE.

1,220,707.

Specification of Letters Patent. Patented June 19, 1917.

Application filed January 31, 1917. Serial No. 145,629.

To all whom it may concern:

Be it known that I, JULIUS FRED HECKMANN, a citizen of the United States, and a resident of Lupus, in the county of Moniteau and State of Missouri, have invented a new and Improved Gun-Magazine, of which the following is a full, clear, and exact description.

My invention has for its object to provide 10 a gun magazine having openings so that the user may at any time ascertain the number of shells or cartridges remaining in the magazine. As the openings are preferably in the under side of the magazine, there is 15 little danger of moisture or foreign matters entering the magazine through the openings, while any foreign matter which may become disposed in the magazine will pass out through the openings when the gun is carried 20 in the usual manner.

Additional objects of the invention will appear in the following specification, in which the preferred form of the invention is disclosed.

25 In the drawings, similar reference characters denote similar parts in all the views, in which—

Figure 1 is a side elevation of a gun provided with my improvement, parts being 30 illustrated in section to show the construction; and

Fig. 2 is an enlarged inverted plan view of the magazine, showing my improvement.

35 By referring to the drawings, it will be seen that the gun 5 has a barrel 6 and a magazine 7 disposed thereunder. The cartridges or shells 8 in the magazine are fed to the breech of the barrel 6 in any ap-

proved manner. In the under side of this magazine 7 there are openings 9 which are 40 spaced apart, one of these openings 9 being disposed under the normal position of each cartridge or shell 8 so that the user of the gun may, by looking at the under side of the magazine, determine at a glance the number 45 of cartridges or shells still remaining in the magazine. A slide handle 10 which slides on the magazine has openings 11 in its under side which register with the openings 9 in the magazine when the slide handle is at rest. 50 In this way the number of cartridges or shells in the magazine may be determined, whether or not the cartridges or shells are in that portion of the magazine which is normally inclosed by the slide handle 10. 55

Not only is it possible by means of the openings 9 to determine the number of cartridges or shells in the magazine, but inasmuch as these openings 9 are disposed in the under side of the magazine, they serve as an 60 outlet for any foreign matter which may enter the magazine.

It is, of course, understood that the slide handle 10 operates in the usual manner to actuate the ejecting and the loading means. 65

Having thus described my invention, I claim as new and desire to secure by Letters Patent:

A gun having a magazine with openings spaced apart at the normal cartridge or shell 70 positions in the magazine, and a slide handle for moving against the magazine and having an opening for registering with one of the openings in the magazine when the slide handle is in normal position.

JULIUS FRED HECKMANN.
